UNITED STATES PATENT OFFICE.

NATHAN L. HOLMES, OF RACINE, WISCONSIN.

WHIFFLETREE.

SPECIFICATION forming part of Letters Patent No. 496,608, dated May 2, 1893.

Application filed March 15, 1892. Serial No. 425,032. (No model.)

To all whom it may concern.

Be it known that I, NATHAN L. HOLMES, of Racine, in the county of Racine and State of Wisconsin, have invented certain new and 5 useful Improvements in Wagon-Evener Connections; and I do hereby declare that the following is a full, clear, and exact description thereof, reference being had to the accompanying drawings, and to the letters of reference marked thereon, which form a part of 10 this specification.

This invention has for its object to provide an improved connection between carriage poles and their eveners and it consists in the 15 several features of construction and in the combinations of devices substantially as hereinafter described and pointed out in the appended claims.

In the accompanying drawings: Figure 1 20 represents my invention in plan view. Fig. 2 is a vertical longitudinal section in the line 2—2 of Fig. 1. Fig. 3 is a vertical section in the line 3—3 of Fig. 1, and Fig. 4 is a section of the evener on the line 4—4 of Fig. 1, looking 25 in the direction of the arrow.

A represents a carriage or wagon pole and B the evener.

C is the strap for supporting the upper end 30 of the bolt D which passes through the evener and pole in the axis of their pivotal connection. As here shown the direct strain of draft is largely taken off the bolt D by the familiar device of a circular boss e rising from the pole plate E into corresponding recess d 35 formed in the pivot plate D' which is fastened to the under side of the evener. For the principal purpose of my invention I supplement these or other pivot devices by a short metal cross-bar F, centrally pivoted at f upon the 40 pole A at the rear of the evener and parallel with it, the ends of the vibratory cross-bar F being connected with the evener on opposite sides of its axis D by means of the metal links G which are pivoted both to the cross-bar 45 and to the evener plate. The cross-bar F is preferably provided with bosses f' at its ends which fit into corresponding holes in the ends of the links G and take the strain imposed upon the cross-bar by the draft upon the 50 evener. Desirably also the plate D' is prolonged and provided with similar bosses d' fitted into holes in the front ends of the links

G. The cross-bar F and the links G thus pivoted to each other, are held together by means of vertical bolts g having washers g' and nuts 55 g'', as shown, and the plate D' and the said links are similarly held together by the bolts d'' passing through the evener and said bosses d' and provided with washers d'' and nuts d'.

The plate D' is shown as being still further 60 extended outwardly and provided at its outer ends with upturned flanges D'' which rise at opposite sides of the evener in close contact therewith to give to said evener direct lateral support at a distance from its central pivot. 65 The front flanges D'' are the ones more directly effective to this end, but the rear flanges are desirable in order that said front flanges may at all times be held by their presence in close bearing contact with the evener. 70

In the construction described not only is the strain largely taken off the central pivot, and particularly is the forwardly tipping strain upon the evener taken from the pivot bolt D and strap C, but the lengthwise tipping tendency of the evener is largely obviated and all the parts are held more perfectly in their original and proper positions with respect to each other. 75

The construction of the cross bar F of metal 80 enables it to be made short and effective without being bungling or in the way while the employment of metal links which are pivoted to the short metal bar F and the metal pivot plate D' enables these parts as well as the 85 bar F to be made so light as to be unobjectionable either on account of their weight or of their appearance and at the same time durable and firm in their connections.

As a further improvement I have shown the 90 strap iron C provided with lateral projections or shoulders e arranged in position to be struck by the rear rounded ends of the links G or by the cross-bar F when the evener has been turned on its central pivot to a desired 95 limit of motion.

I claim as my invention—

1. The combination with a pole and an evener provided with a pivot plate, of a metal cross-bar centrally pivoted to the pole parallel 100 with the evener, and metal links pivotally connecting the ends of the cross bar with the pivot plate of the evener on opposite sides of the axis of the latter.

2. In combination with a pole, an evener-bar having a central pivotal connection with the pole, and an evener-plate secured to the under side of the evener-bar; said evener-plate being prolonged in opposite directions from its pivot and longitudinally of the evener-bar, and being also provided with upturned flanges located remotely at opposite points from the pivot of the evener-bar and near the ends of the plate, said flanges bearing laterally against the evener-bar at points remote from the pivotal point of said bar, and between the pivot and the ends of the bar, substantially as set forth.
- 15 3. The combination of a pole, an evener provided with a plate D', a cross-bar F centrally pivoted to the pole parallel with the evener, and links pivotally connecting the ends of said cross-bar with the plate D'.
- 20 4. The combination with the pole A, interfitting pivot plates D' and E affixed respectively to the evener and pole, a bolt D holding

the evener to the pole, a cross-bar F centrally pivoted to the pole, links G pivotally connecting the ends of the bar F with the plate 25 D', and flanges D² formed on the plate D' and rising in contact with the front face of the evener.

5. In combination with the pole, the evener, the cross bar and the links connecting the 30 cross-bar with the evener, an iron secured to the pole and provided with shoulders arranged in the path of one of the vibrating parts connected with the evener whereby the latter may be arrested at a desired limit of 35 movement upon its pivot.

In testimony that I claim the foregoing as my invention I affix my signature in presence of two witnesses.

NATHAN L. HOLMES.
